UNITED STATES PATENT OFFICE.

CALVIN S. PAGE, OF PONTIAC, ILLINOIS.

BICYCLE.

SPECIFICATION forming part of Letters Patent No. 496,616, dated May 2, 1893.

Application filed October 19, 1892. Serial No. 449,367. (No model.)

To all whom it may concern:

Be it known that I, CALVIN S. PAGE, of Pontiac, in the county of Livingston and State of Illinois, have invented certain new and useful 5 Improvements in Bicycles; and I do hereby declare that the following is a full, clear, and exact description thereof, reference being had to the accompanying drawings, and to the letters and figures of reference marked 10 thereon, which form part of this specification.

This invention is an improvement in bicycles, and its objects are, first, to provide an improved "drive," by which the machine can be propelled through the medium of oscillating or vibrating pedals; second, to have one pedal raise during the depression of the opposite pedal without the employment of lifting springs; third, to improve the construction of the frame; fourth, to provide improved 20 anti-friction bearings for the drive-wheel on its axle.

The invention therefore consists, first, in the novel construction of the propelling gear, and combination of parts therein; by which 25 the above second and fourth objects are attained: second, in the novel construction of the frame; all of which will be hereinafter specifically described, reference being had to the accompanying drawings by figures and 30 by letters of reference marked thereon to designate parts referred to by such figures and letters in the description.

Figure 1 represents a side elevation of the complete bicycle, of the "safety" type, embodying my improvements. Fig. 2 is an enlarged view of the driving wheel, hub and axle, with the outer shell removed. Fig. 3 is a longitudinal vertical sectional view on line 3—3 Fig. 2. Fig. 4 is a detail sectional view 40 of the ratchet mechanism detached. Fig. 5 is a detail view of a part of such mechanism. Fig. 6 is a detail.

The frame.—The frame of the machine is roughly diamond shaped. Its rear members 45 A, A', are bifurcated to straddle the rear or driving wheel Y, and are rigidly connected at their rear ends to the axle, and to each other. The front members A², A³, are connected at their rear ends to the front ends of members 50 A, A', respectively, and at their front ends to

the rearwardly inclined sleeve A⁴ through which passes the steering rod A⁵ the lower end of which is bifurcated and is connected to the axle of the front wheel Z. A handle bar is secured to the top of this steering rod as 55 shown. A⁶ is a combined mud-guard and brace, connected at its ends to the points of junction of members A, A² and A', A³, respectively. The several members of the frame are preferably made tubular, and welded together at their junctions. Ordinary mud-guards are attached to the frame as indicated, and the wheels may be of any desired construction. The saddle bar a is connected to the upper end of member A, and its upper 60 end a' is bent horizontally backward. The saddle is clipped onto this portion a', in any suitable manner.

The drive mechanism.—The rear axle C, on which wheel Y is mounted, is stationary, and 70 its ends are secured to the bifurcations of member A of the frame in any suitable manner. To the center of this axle is rigidly secured a transverse shaft D, projecting equally on each side of the axle, and having a central 75 cylindrical enlargement or boss d through which the axle passes. The ends of this boss are concaved at the meeting edges of their sides and face as shown at d'. Upon axle C at each side of boss d are placed sleeves E, E' 80 whose bore is of greater diameter than the axle around which they revolve freely. The inner ends of said sleeves are about equal in diameter to boss d and are concaved as shown at e opposite grooves d' and a series of anti-friction balls 2, 2, are confined in and between the concaved ends d', e, of the boss and sleeve as shown in Fig. 3. Concaved rings e' are fitted in annular recesses e² in the outer ends of the sleeves, and a series of anti-friction 85 balls 3, 3, are confined between said rings and concaved faced nuts e³ screwed on the threaded ends of the axle as shown. By this means the sleeves E, E' are supported on but out of contact with the axle by anti-frictional 90 ball bearings. On the outer ends of sleeves E, E' are formed or secured small band pulleys F, F' hereinafter referred to. On the inner ends of the sleeves E, E' respectively are rigidly secured bevel gears G, G' which inter- 95 100

mesh with similar bevel gears g , g' journaled on the opposite ends of shaft D so that when sleeve E turns in one direction sleeve E' must revolve in the contrary direction, and vice versa. Gears g , g' are confined to the shaft G by means of nuts g^2 provided with suitable washers and nut-locks g^3 , or other suitable means employed to retain the gears on said shaft. H , H' designate the hub end plates each being annular and fitted loosely on said sleeves E , E' respectively, to the inside of pulleys F , F' . The plates are supported on the sleeves by means of the annularly concaved bearing rings h , and f , the latter being fitted around the sleeves against the inner face of pulleys F , F' , and the former being fitted into the central openings of plates H , G' , a series of anti-frictional balls 4 , 4 , being confined between the rings as shown. Each ring h is provided with a flange h' by which it is kept in position within the hub plates. Screws f' are tapped through the webs of pulleys F , F' and bear against the rings f and by means of these screws the latter rings can be adjusted in relation to rings h , so as to equalize the pressure on balls 4 , 4 . The plates H , H' are connected at their peripheries to a cylindrical hub shell H^2 in any suitable manner, said shell and plates forming a hollow hub and inclosing and protecting the working parts and ball bearings from dust and grit. It is also provided with circumferential flanges H^3 to which the spokes may be connected in any manner desired. Four or more or less slots H^4 are formed in plates H , H' and in these slots are placed dogs or pawls I , I' shown more clearly in Fig. 4. These dogs are about as wide as the plates are thick, but each has an outwardly projecting tooth i on its outer edge near one end, and its other end is recessed as at i' to fit a corresponding projection or tooth H^5 at the rear end of the slot in which it is confined. The slots are made of such size that when the pawls are inserted therein the toothed ends of the pawls can be swung back and forth or rocked on teeth H^5 while the other end is retained in the slot. The corner of pawl I opposite tooth i is recessed as at i' to enable the pawls to be easily slipped in place. When the pawls are swung outward they respectively engage with ratchet faced rings J , J' secured to or formed on the inner faces of pulleys F , F' , as indicated in Fig. 3. The pawls are prevented from swinging so far inward as to drop from slots H^3 by means of annular disks K , K' located to the inside of and opposite plates H , H' respectively. These disks are supported on gears G , G' respectively by means of pins k , k' , which rest loosely in holes G^2 in the outer faces of said gears as shown in Fig. 3. The disks however are permitted a slight amount of lateral movement toward and from plates H , H' and when moved toward said plates will rock the pawls and cause them to engage their ratchets. To the inner face of disk K' and near its periphery are attached arms k' which extend parallel with the axle across nearly to disk K , said rods being of such length that when one disk is moved inward, the other disk will be through the agency of said arms or rods, forced outward, so that if either disk be fully shifted so as to allow the pawls in the adjoining plate to disengage their ratchet, the pawls of the opposite plate will be forced into engagement with their ratchet. Preferably the free ends of rods k' are provided with friction rubbers or rollers k^2 . Openings or recesses K^2 are made in disk K at the same relative points as rods k' on disk K' , there being one opening for each disk. The ends of said openings are beveled as shown in Fig. 7 so that the rods will ordinarily move therewithout without catching therein. The object of such openings will be explained hereinafter. The pedal levers L , L' as shown are oscillating levers and are fulcrumed on studs a^5 attached to the bifurcations of the lower member A' of the frame in front of the axle, as shown. The rear ends l of said levers are bent inwardly so as to pass between the bifurcations of member A of the frame, and the wheel. To the end l of each lever is attached one end of a chain or band l^2 , which is wrapped around and its other end secured to the pulley F or F' adjoining the lever. Ends l may be perforated as at l' to enable bands l^2 to be adjustably connected thereto. The front ends of said levers are curved as desired so as to bring the pedals attached thereto near the rear wheel and out of the way of front wheel. A^7 , designate rods connected at their upper ends to the frame near the seat, and at their lower ends to the studs a^6 so as to partly relieve the latter and member A' of strain.

Operation: Upon the depression of either pedal the pulley to which it is connected is rotated in a forward direction. Supposing F to be thus rotated, sleeve E is similarly rotated, but sleeve E' is rotated in a backward direction thereby raising lever L' , and at the same time, pawls I' riding up on the teeth of ratchet J' are rocked inward, thereby forcing disk K' away from plate H' , and the inward movement of disk K' through rods k' , forces disk K toward plate H , and thereby force pawls I to engage the ratchet J , and thus motion is imparted to the wheel in a forward direction. Upon the depression of lever L' the movement of all the parts is exactly reversed except that pawls I' now engage ratchet J' and impart forward movement to the wheel. If the levers L , L' be stopped when the pedals are in line, it will bring rods k' opposite the openings k^4 and rollers k^2 will slip into recesses K^2 as indicated in Fig. 7, consequently both sets of pawls I , I' can slip over their ratchets and the working parts remain at rest, the wheel revolving freely on the ball bearings 4 , 4 . The pedals can then be used as rests for the feet.

Having described my invention, what I claim as new, and desire to secure by Letters Patent thereon, is—

1. The combination of the axle, the transverse shaft attached centrally thereto, the sleeves on said axle at opposite sides of said shaft, the gears on the inner ends of said sleeves, gears on the opposite ends of said shaft meshing with the gears on the sleeve, 5 the hub end plates loosely mounted on said sleeve, the pawls mounted on said plates, the annular ratchets mounted on the sleeves, and the levers and connections for rotating said sleeves, and means substantially as described.
- 10 15 20 25 30 35 40 45 50 55 60 65 70 75 80 85 90 95 100 105 110 115 120 125 130
2. The combination of the axle, a shaft fixed transversely thereto having a central enlargement, a gear on said shaft and the sleeves on said axle at opposite sides of said enlargement, the nuts confining said sleeves on the axle, and the ball bearings between the inner ends of said sleeves and the enlargement, and the outer ends of said sleeves and the nuts and gears on the inner ends of said sleeves meshing with the gears on the shaft, substantially as and for the purpose set forth.
3. The combination of the axle, the transverse shaft connected thereto, the sleeves revolvably mounted on said axle at opposite sides of the shaft, the gears on the ends of said shaft meshing with the gears on the sleeves, and the hub plates revolvably mounted on said sleeves, substantially as described.
4. The combination of the axle, the shaft fixed transversely thereto having a central enlargement, and the sleeves on said axle at opposite sides of said enlargement, the gears on the inner ends of said sleeves and a gear on said shaft meshing therewith, the nuts confining said sleeves on the axle, and the ball bearings between the inner ends of said sleeves and the enlargement, and the outer ends of said sleeves and the nuts, and the hub end plates revolvably mounted on the sleeves, and the pawls and ratchets for locking said plates to the sleeves and mechanism for revolving said sleeves, substantially as described.
5. The combination of the axle, the transverse shaft connected thereto, the sleeves revolvably mounted on said axle at opposite sides of the shaft, the gears on the ends of said sleeves, the gears on the ends of said shaft meshing with the gears on the sleeves, and the hub plates revolvably mounted on said sleeves, and ball bearing substantially as described between said sleeves and axle, and between said hub plates and sleeves, substantially as specified.
6. The combination of the axle, the transverse shaft connected thereto, the sleeves revolvably mounted on said axle at opposite sides of the shaft, the gears on the ends of said

sleeves, the gears on the ends of said shaft meshing with the gears on the sleeves, and the hub plates revolvably mounted on said sleeves; with the levers and connections for rotating said sleeves, and the pawls and ratchets for locking said plates to said sleeves, substantially as and for the purpose described.

7. The combination of the axle, the revolute sleeves mounted thereon, gearing for transmitting motion from one sleeve to the other in opposite directions, the hub plates revolvably mounted on said sleeves and the ratchets and pawls for transmitting motion from the sleeves to the hub plates, with the disks attached to said sleeves and laterally movable, and means for causing said disks to move simultaneously in the same direction whereby the pawls of one hub-plate will be automatically thrown into engagement with its ratchet when the pawls of the opposite plate disengage their ratchet, substantially as and for the purpose described.

8. The combination of the axle, the transverse shaft connected thereto, the sleeves revolvably mounted on said axle, at opposite sides of the shaft, the gears on the ends of said sleeves, the gears on the ends of said shaft meshing with the gears on the sleeves, and the hub plates revolvably mounted on said sleeves, the pawls attached to said plates, the ratchets connected to said sleeves exterior to said plates, and the laterally movable disks K, K' and their connections, substantially as described.

9. The combination of the axle, the revolute sleeves on opposite sides thereof, the gearing between said sleeves, and the ratchets attached thereto; with the wheel hub consisting of the cylindrical barrel having spoke attaching flanges, and annular end plates or heads revolvably mounted on said sleeves, and the pawls attached to said plates adapted to engage the ratchets, substantially as and for the purpose specified.

10. The combination of the axle, the sleeves, on opposite ends thereof, the pulleys on the outer ends of said sleeves, and bevel gears on the inner ends thereof, and an intermediate gear meshing with the gears on both sleeves, with the pedal levers connected to said pulleys, whereby, upon the depression of one lever the other is automatically raised, substantially as and for the purpose set forth.

11. The combination with the axle, the opposite sleeves thereon, the gearing between said sleeves, the hub plates loosely mounted on said sleeves, and the ratchet and pawls for transmitting motion from the sleeves to the hub plates; with the laterally movable disk K having openings K⁴ and the opposite similar disk K' and arms k', and the levers and connections for rotating said sleeves, all constructed substantially as described so that the power of the levers is alternately communicated to the hub plates and yet the pawls be disengaged when the levers are stopped on

a level, substantially as and for the purpose described.

12. The combination with the revoluble ratchets J, J' and the revoluble hub plates H, H': of the pawls I, I' mounted in openings in said plates and the disks K, K' and rods k' for shifting said pawls, all substantially as and for the purpose described.

In testimony that I claim the foregoing as my own I affix my signature in presence of two ~~to~~ witnesses.
